(57) **CLAIM**

The ornamental design for a high security anti-splash system cuffing box, as shown and described.

DESCRIPTION

FIG. 1 is a perspective view of a high security anti-splash system cuffing box, showing my new design;

FIG. 2 is a front elevation view thereof;

FIG. 3 is a left side elevation view thereof, the right side elevation being a mirror image thereof;

FIG. 4 is a top plan view thereof; and,

FIG. 5 is a bottom plan view thereof.

The broken lines of even length depict environmental subject matter that forms no part of the claimed design, while the dash-dot-dot-dash lines shown in the drawings depict portions of the high security anti-splash system cuffing box visible through transparent material and forms no part of the claimed design.

No rear elevation view is shown as it is not visible during use, flat and unornamental, and so forms no part of the claimed design.
